UNITED STATES PATENT OFFICE

154,260

DESIGN FOR A RUBBER PLAY BALL

Joseph M. Gapstur, John W. Booker, and
Charles W. Ebert, Ashland, Ohio

Application January 19, 1948, Serial No. 143,885

Term of patent 14 years

(Cl. D34—15)

To all whom it may concern:

Be it known that we, Joseph M. Gapstur, Charles W. Ebert, and John W. Booker, citizens of the United States and residing at Ashland, in the county of Ashland and State of Ohio, have invented a new, original, and ornamental Design for Rubber Play Ball, of which the following is a specification, reference being had to the accompanying drawing, forming part thereof:

Fig. 1 is a front view of the rubber play ball showing our design;

Fig. 2 is a side view of the rubber play ball; and
Fig. 3 is a top view of the same.

We claim:

The ornamental design for a rubber play ball, as shown.

JOSEPH M. GAPSTUR.
JOHN W. BOOKER.
CHARLES W. EBERT.
